UNITED STATES PATENT OFFICE

2,429,625

PROTECTOR FOR LADIES' STOCKINGS

Jacque E. Horn, New York, N. Y.

Application April 13, 1944, Serial No. 530,814

1 Claim. (Cl. 2—61)

1

This invention relates to improvements in protectors for ladies' stockings, and more particularly to an article capable of efficiently performing its protecting function on all parts or sections of the stocking when in use and of being folded or rolled into a small package capable of being carried in the handbag or pocket-book or purse when not in use.

Heretofore various types of stocking protectors have been proposed, such as leggings, and in some cases such leggings have embodied foot portions; but those devices embodying foot portions cover the upper portion of the shoe of the wearer as well as the stocking and necessarily either embodied an opening for the passage of the heel of the shoe or had fastening elements for fastening the device to the outside of the shoe.

One of the objects of my invention is to produce a protector of the type specified which has a foot portion intended to be worn beneath the shoe and is provided with an integral heel section fitting and engaging the heel of the wearer to retain the lower end of the device in proper position.

Another object of my invention is to provide, in a device of the character specified, an integral heel section having the conformation of a spherical segment that will closely conform in shape to and fit the heel of the wearer and thus to utilize the heel of the device as an anchoring or a retaining portion for the lower end of the protector without the use of extraneous fastening devices or the like.

Still another object of my invention is to produce a protector of the type specified having a toe-protecting section capable of use when desired but connected to the heel portion by an integral, narrow and elastic but readily-severable strap to enable the wearer to remove the toe section, if and when desired.

Still another object of my invention is to produce a protector of the type specified having a foot portion, intended to be worn inside the shoe of the wearer and provided with integral ankle and heel sections adapted automatically during application of the protector to engage the heel and ankle sections for the purpose of holding the lower end of the protector in place, and also having a substantially open section extending over and across the instep or metatarsal section as well as across the arch of the foot for the purpose of ventilating and avoiding the heating of the foot that would occur if the middle portion of the foot were completely covered by waterproof material, while providing protection

2

for sections of the instep and heel that are exposed by certain types of shoes.

With these and other objects in view, the invention comprises the combination of members and arrangement of parts so combined as to co-act and cooperate with each other in the performance of the functions and the accomplishment of the results herein specified, and comprises in its adaptations the species illustrated in the accompanying drawings, in which:

Fig. 1 is a view in side elevation showing my protector for ladies' stockings in unrolled condition;

Fig. 2 is a view in side elevation of my protector showing the leg portion rolled down and the foot portion being applied to the foot of the wearer;

Fig. 3 is a view of the article shown in Figs. 1 and 2 with the entire protector including the leg portion in place on the wearer;

Fig. 4 is a bottom plan view of the unapplied protector shown in Fig. 1; and

Fig. 5 is a bottom plan view of the protector in applied position as shown in Fig. 3.

Referring now to these drawings, which illustrate a preferred embodiment of my invention, 10 indicates a protector of my invention preferably composed entirely of thin, waterproof material, such as high-grade transparent and elastic rubber. The article comprises, as shown, a leg portion 10a of elongated tubular or substantially 20 cylindrical conformation and a foot portion 11 integral therewith and composed of an ankle section 11' flaring outwardly and downwardly and merging with a heel section 12 having the shape of a segmental sphere adapted to engage and fit 30 the similarly shaped heel of the wearer and a cap or hood-shaped toe section 13 isolated from the heel and ankle sections and connected thereto at the bottom of the protector by a relatively thin integral strap 14.

40 All of the parts of my protector are elastic and thin and my protector is adapted to be directly applied over the stocking foot of the wearer and the foot portion 11 is intended to be worn beneath and within the shoe.

45 In many forms of ladies' shoes, the heel section is open to expose the stocking and in other types of ladies' shoes, the toe and heel sections are both open and exposed and it is the purpose of my invention to protect the stockings of the 50 wearers of both types of shoes, and also to enable a wearer who uses only the type exposing the heel, to eliminate the toe-protecting portion of the protector.

In the preferred form of my invention, the 55 leg portion 10a is of somewhat heavier material

than the foot portion which though formed integrally and merging with the leg portion is composed of highly elastic and very thin material to enable the same to be worn within the shoe as aforesaid and the said segmentally-spherical heel section is adapted to elastically grip the stockinged heel of the wearer and to automatically fasten the lower foot portion on the foot of the wearer while the forward part of the foot first extends through the opening 16, the edges of which are suitably finished to prevent tearing and to maintain a flattened relationship on the foot. If the toe portion of the stocking is exposed by the shoe, then the cap-shaped toe section is applied, as shown in Fig. 2 and the roll 17 is unrolled and moved upwardly on the leg of the wearer.

As illustrated the upper edge of the leg portion is finished with an integral rib which may be hollow, if desired, and this rib will serve as an axis about which the leg portion of the protector may be rolled down on the leg and also may be rolled initially about a form to produce a small, tight package that may be carried in the purse or pocketbook of the wearer.

The operation of the device will be obvious from the foregoing description and it will suffice to say that when the protector is rolled up, it may be applied as shown in Fig. 2 whereupon the heel of the wearer will be automatically gripped by the heel section of the protector, the toe section may, if being used, be slipped over the toe and the leg portion will then be rolled up on the leg. To remove the protector, the operation or movement of rolling is reversed.

Having described my invention, I claim:

A protector for ladies' stockings embodying, in combination, a leg portion comprising an elongated one-piece tubular body of thin elastic waterproof material, adapted to enclose the leg and to snugly fit over the upper parts of the stocking of the wearer, and provided at its top with an opening to permit the downward insertion of the foot and leg, a foot portion having an ankle-covering section formed integrally with

4
said leg portion and a heel-section integrally connected to said leg and ankle section and having a conformation adapted to fit the heel snugly over the stocking and to automatically grip the stocking and foot of said wearer to retain and anchor the protector in position beneath the vertical axis of the leg portion, said foot portion being provided with a foot outlet opening extending at the bottom of the foot from said integral heel and ankle sections forwardly to the forward extremity of the foot, whereby, in the operation of applying the protector, a wide opening is provided for free projection of the entire bottom portion of the foot forwardly of the heel section while guiding the heel section into position, said foot portion also having a short toe-enclosing section connected with said heel section by a relatively narrow integral elastic strap extending beneath the sole of the foot whereby the toe-section may be severed from the heel section to cooperate with shoes having covered toes and may be retained to cooperate with shoes having open toe portions.

JACQUE E. HORN.
